UNITED STATES PATENT OFFICE.

MARTIN THUM, OF ROCHESTER, NEW YORK.

COMBINATION DESK AND CHAIR.

1,195,626.

Specification of Letters Patent. Patented Aug. 22, 1916.

Application filed April 14, 1915. Serial No. 21,461.

To all whom it may concern:

Be it known that I, MARTIN THUM, a citizen of the United States, and resident of Rochester, in the county of Monroe and State of New York, have invented certain new and useful Improvements in Combination Desks and Chairs, of which the following is a specification.

This invention relates to a combination desk and chair, particularly adapted for typewriter use and for school-rooms. Its object is to fix the desk and chair in proper relation to each other and at the same time have them movable as a unit; to eliminate parts of each, and so to cheapen the cost of manufacture; to produce a construction that is automatically adjustable for uneven floor surfaces; and to provide a construction, of the character described, in which provision may be made for adjustment of the several elements of the chair and desk separately and with reference to each other, and to provide for the substitution of different desk-tops according to requirements.

In the drawings:—Figure 1 is a perspective view of the combined desk and chair; Fig. 2 is a detail enlarged; and Fig. 3 is a section on the line 3—3 of Fig. 2.

The invention comprises the desk-top 1 with a standard 7 that is provided with legs 5, 5, the revolving chair 8 provided with the legs 12, 12, and means for supporting the chair in position in front of the desk by pivotal attachment to the desk-standard.

The side brackets 2, 2, which are attached to the top, are shaped at 3, 3 to fit around the standard 7, and the top is adjustable vertically upon the standard by means of screws 4, 4 which enter inserts 21, 21 located, respectively, in the ends of the standard, thereby clamping the top in set position. It is obvious that tops of different forms, adapted for different uses, may be substituted one for another upon the standard.

The chair is attached to the standard by means of a support 11 which is pivoted by the bolt 15 to the standard 7 beneath the plate 16. A plate 13 is attached to the support 11, beneath its pivotal point. This plate has a curved slot 17 at each end through each of which a bolt extends that projects from the standard 7, and a nut 18 and a suitable spring washer on each bolt exert frictional resistance to the movement of the plate with respect to the bolts. The support 11 is carried down from the desk-

standard adjacent to but clearing the noor, and then forwardly and upwardly to the socket 20 within which the spindle 9 of the chair rotates. The support 11 is rigidly attached to said socket 20; and the legs 12, 12 are also attached to said socket 20. The combined desk and chair are thus supported at the front by the legs 5, 5, and at the rear by the legs 12, 12, and the pivotal connection of the support 11 with the standard 7 at 15 causes the support 11 to turn under the weight of the person occupying the chair till both legs 12 come into contact with the floor, should one of the legs 5 be higher than the other, the nuts 18 affording sufficient frictional resistance to the turning movement to cause the parts to retain the relative positions they assume. The height of the chair-seat 8 is vertically adjustable by means of a collar 10. This construction, besides affording the advantage pointed out above, is capable of accurate adjustment as to the height of the desk-top, and also as to the height of the chair-seat, and also the relative heights of these parts. It is also capable of being moved from one location to another without disturbing these adjustments. The seat is easily accessible and easily left, and nothing is in the way of the body or limbs of a person when seated at the desk. Finally, the top and its standard, and the chair and its support, may all be taken apart readily, and packed together compactly for storage or shipment.

The object of the pivotal attachment of the yoke with the desk is to permit the four legs of the combined desk and chair to accommodate themselves to inequalities in the floor-surface on which they rest, as above described. This accommodating movement is permitted both by the pivot 15 and by the mode of connection of the brace 13 with the board 7. At the same time, however, the brace rigidly supports the yoke against any swinging movement, with respect to the desk, other than that about the axis of the pivot 15. The hand-nuts 18 are preferably tightened to such a degree as to press the brace closely against the board and subject the parts to friction through the action of the spring-washers, while at the same time permitting sufficient freedom of movement for the desk and chair to accommodate themselves to the floor-surface when subjected to the weight of the user. If, however, the desk and chair are to be kept permanently in

one position the hand-nuts 18 may be set, limiting the swinging movement of the chair tight, after the necessary preliminary adjustment upon its pivot, substantially as shown and described.

The combined desk and chair herein disclosed contains, in addition to the features claimed as novel, certain features of construction which constitute the subject-matter of an application for Letters Patent of the United States filed by me October 29, 1915, Serial No. 56,644, and these features are accordingly not claimed herein.

I claim:

1. The combination of a desk and a chair, each provided with means for supporting it against lateral tilting but not against tilting in a forward and rearward direction, and means connecting the desk and the chair and adapted to prevent all relative movement except relative rotation about a substantially horizontal axis.
2. A combination desk and chair, comprising a standard with two legs and a desk-top attached thereto, a chair having two legs detachably connected with the desk-standard and adapted to swing in a plane parallel with that of the legs of the latter, substantially as shown and described.
3. A combination desk and chair, comprising a desk having a standard with two legs, a chair having two legs, means for attaching the chair pivotally to the desk-standard in position in front of the desk, and means for
4. A combination desk and chair, comprising a desk having a standard with two legs, a chair having two legs, means for attaching the chair pivotally to the desk-standard in position in front of the desk, and frictional means for resisting the swinging movement of the chair upon its pivot, substantially as shown and described.
5. The combination of a desk provided with legs located adjacent to its sides; a chair provided with two legs; and a support extending between the chair and the desk and clear of the floor-surface, the support being attached rigidly to the chair and pivoted to the desk upon a horizontal axis.
6. The combination of a desk having two legs and a flat vertical standard connecting the legs; a chair provided with legs; a support rigidly attached to the chair and extending to said standard; a pivotal connection, on a horizontal fore-and-aft axis, between the support and the standard; arms extending laterally from the support, parallel with the standard; and means for securing the ends of the arms to the standard, said means being adapted to permit the arms to swing in a vertical plane.

In testimony whereof, I affix my signature.

MARTIN THUM.
